UNITED STATES PATENT OFFICE.

JOSEPH LEMBLÉ, OF SENNHEIM, GERMANY.

ELECTRIC TYPE-WRITER.

No. 884,742.

Specification of Letters Patent. Patented April 14, 1908.

Application filed May 25, 1907. Serial No. 375,625.

To all whom it may concern:

Be it known that I, JOSEPH LEMBLÉ, a subject of the Emperor of Germany, and resident of Sennheim, Alsace, Germany, have 5 invented new and useful Improvements in Electric Type-Writers, of which the following is a full, clear, and exact specification.

The advantages of the electric typewriter are well known. The power to effect the 10 impressions from the type is not furnished by the hand of the operator, but is automatically obtained by electrical power on the movement of the keys. The result is that the keys can be struck legato and not staccato, that is to say, more lightly, conveniently and quickly than hitherto. The 15 strength of the impressions is also independent of the strength of the blow applied to the keys, so that the impressions are uniform 20 throughout.

The chief difficulties in the electric typewriters with type-wheel or drum hitherto proposed lie in the manufacture of the current contacts for the type adjustment of the 25 cylindrical type-carrier, the hammer device for effecting the type impressions, the paper carriage controlling mechanism and the final cutting off of the current. It has not yet been possible in connection with a series of 30 keys to control all the contacts necessary for a complete operation in such a manner that they are each mechanically closed independently of the other, that is to say, independently of one another and of magnet armatures, relays and the like. This problem is 35 solved by the electric typewriter forming the subject of this invention. To this end a group of key-levers through the medium of a common intermediate rocking shaft acts in 40 conjunction with one and the same contact wheel arranged to control a triple contact in such a manner that on the depression and release of any one of the key-levers the said contact wheel is displaced and directly 45 effects a first contact for the adjustment of the type-carrier, a second contact for the paper carriage controlling mechanism and a third for the return of the type-carrier to its initial position and the locking of the same 50 and also for cutting off the current.

In the accompanying drawings: Figure 1 is a plan view of an electric typewriter constructed according to the invention. Fig. 2 is a vertical section on the line A—B, Fig. 1. 55 Fig. 3 is a plan view of a part of Fig. 1, the paper carriage, type-carrier, its guides and

the carrier retaining pins appertaining to the key-levers are removed. Fig. 4 is a front view of the type-carrier and of a part of its guide-frame. Fig. 5 is a transverse section 60 on a larger scale of a part of the type-carrier and its guide-frame, the said section being made on the line C—D of Fig. 4. Fig. 6 is a rear elevation on a larger scale of a part of the guide-frame for the type carrier. Fig. 7 is a 65 vertical section on a larger scale made in Fig. 1 through a guide-bar for a type-carrier controlling rack and through guide-bars for contact slides, showing the said rack with type-carrier keeping arms in elevation. Fig. 8 is 70 a section on the line M—N of Fig. 7. Fig. 9 is a detail section on the line E—F of Fig. 3, seen in the direction of the arrow u. Fig. 10 is a detail section on the line G of Fig. 3. Fig. 11 is a detail section on the line H—I of 75 Fig. 3, drawn to a larger scale and showing the contact wheel device. Fig. 12 is a vertical cross section on the line E—F of Fig. 3, seen in the direction of the arrow t. Fig. 13 is a horizontal section through the contact 80 wheel device and the type-carrier drive, on the broken line K—L of Fig. 11. Fig. 14 is a diagrammatic view illustrating the electric circuit and connections.

The keyboard of the machine is divided 85 into two groups of keys, a left hand group and a right hand group; to both groups of keys there are common the type-carrier, which like a weaving shuttle is movable or 90 slideable in a right and left hand direction; the type striking device; and the paper carriage controlling device, while the contact devices and the electric type-carrier drive are separately provided for each group of 95 keys.

In the following description, for the sake of simplicity, only one group of keys, that is to say, the left hand group, is described.

The key-levers 1 (Figs. 1 and 2) are 100 loosely pivoted upon the rods 2 and each is provided with a projection 3 which extends backwards beneath the stirrup 4 of a rocking shaft 5 common to all of them; each of the 105 said levers 1 is positively connected by means of a link 6 with a bell-crank lever 7 so that when a key is depressed the rocking shaft 5 is turned in the direction of the arrow x and the lever 7 appertaining thereto in the direction of the arrow y (Fig. 2). The free arms 110 of the bell-crank levers 7 project through an upper frame-plate 8 which protects the inner contact devices, the said arms terminating

opposite a series of pins 9 which, when the levers 7 are swung out in the direction of the arrow *y*, are pressed backwards by the said levers in opposition to the action of springs 10, (Fig. 1). The pins 9 serve a double purpose. Firstly, when in their rearmost position, they have to retain the type-carrier in such a position that the type corresponding to the key struck is brought directly in front 10 of a type striking hammer, to which end the distribution of the keys and the arrangement of the types in the type-carrier are suitably chosen; secondly simultaneously with the retaining of the type-carrier the said pins 15 serve to close an electric circuit for actuating the type striking hammer. The pins 9 are longitudinally movable in rails 11 carried by, but insulated from, the upper frame-plate 8 which, together with the machine frame, is 20 in connection with one pole of the source of current. They have at their front end where they are struck by the bell-crank levers 7, a head 12 of insulating material, so that they are completely insulated from the machine 25 frame and the parts mounted therein.

The type-carrier contains three superposed rows of movable types viz., an upper row containing types of the smaller alphabet, a middle type row of the larger alphabet and 30 a lower row of types for other characters. It is horizontally movable in the direction of its length in a guide-frame, the upper and lower guides or rails 14 of which are of a U-shape, the said frame being also provided 35 with rear bars 15 (Figs. 4 and 5). The guide-frame, 14; 15, for the type-carrier is arranged so that it can be vertically adjusted on upright pins 17, by means of lateral lugs 16, whereby it is possible to so adjust the type-carrier, the upper row of types of which (small alphabet) is usually at the height of the head of the type striking hammer, that the middle or lower row of types can be brought 40 to the level of the said hammer head. This 45 vertical adjustment of the type-carrier guiding frame is effected by means of two special key-levers 18 and 19 (Fig. 1), of which the lever 18 is pivoted at the point 20 and enables the middle row of large alphabet types 50 to move to an extent corresponding to the ratio of its length of arms, while the key-lever 19 is pivoted at 21 and allows the bottom row of types to move to an extent corresponding to the much longer rear arm of 55 the lever; the stroke of these key-levers is advantageously limited by means of adjustable stops 22 shown in Figs. 1 and 2. It will be seen from these figures that the rear arms of the levers 18 and 19 are connected 60 with the parts 16, and serve to elevate the type-carrier frame to the appropriate position to bring the middle and lower rows of type into place. The type-carrier frame extends substantially the whole width of the 65 machine as shown in Fig. 1, and the bars 17

which serve as guides for the type-carrier frame are arranged at each side of the machine. Fig. 2 illustrates the type-carrier in its lowermost position. Upon depression of the lever 18, the frame 14 will be elevated 70 about one-third of its height, while on depression of the lever 19 it will be elevated to its uppermost position.

The arrangement of the types in the type-carrier is best seen in Fig. 5, which is a section on the line C—D, Fig. 4, drawn to a larger scale. Each type 23 is mounted upon a supporting rod 25 by means of a plate 24; the front end of this rod projects out of the carrier guiding frame in order to be subjected to the action of the striking hammer, and the said rod is provided with a return spring 26 which tends to retain the type in the position indicated. When a type rod 25 is struck by the hammer, the corresponding type is pushed out from the rear of the carrier guiding frame against the action of the spring 26, recesses 27 (Fig. 6) being provided on the flange portions of the rails 14 and bars 15 for the free passage of the type 90 plate 24 so that the rearwardly projected type by means of an ink strip or band 28 (Fig. 1) passing at the back of the carrier guiding frame, effects the impression upon the paper of the paper carriage. In order 95 that the types shall not rock about their rod, each of the type plates 24 is provided with a guide pin 29 which is parallel to the rod 25 and insures its rectilinear movement in the type-carrier. The types can only be projected backwards from the carrier-frame in the position in which they are opposite the striking hammer and this through the medium of the recesses 27, while at other 100 points of the carrier guiding frame they are prevented by their plates 24 from moving over the flange parts of the rails 14 and over the bars 15. The type-carrier is advantageously mounted on rollers in the guide frame to insure its easier movement. 110

The type striking device consists of a hammer 31 (Fig. 2) pivotally mounted at the point 30 and an electromagnet 32 arranged beneath the frame-plate 8, the armature 33 of the said magnet being connected with the hammer 31. When the electromagnet 32 is energized it attracts the armature 33 and thereby causes the hammer 31 to swing in such a manner that its head strikes against the rod 25 of the type which has been 115 brought in front of it by the adjustment of the type-carrier so as to effect an impression. When the energization of the magnet 32 ceases, the hammer 31 returns to its position of rest on to an elastic buffer pad to 120 prevent noise.

The operation of the type-carrier in order to bring it to the operative position corresponding to the particular key actuated is effected by means of an electromagnet 130

through the medium of toothed gearing. To this end a rack 36 is mounted above the frame-plate 8 upon a round rod 35 (Figs. 1, 2, 7 and 8) upon which it can be longitudinally moved, the said rack being supported at the rear by a guide roller 60 and having engaging with it a toothed sector 37. The rack 36 is detachably coupled at each of its ends by means of a finger 38 with the stirrup 39 of a slide 40 which is movable upon two guide-bars 41 and 42 and carries a contact spring 43. By displacing the rack 36 the slides 40 are carried with it along their guide-bars in order by means of their contact spring 43 to make a secure contact with the type-carrier retaining pin 9 which is pressed backwards by the operation of a key-lever. The rack 36 also carries at its ends two keeping arms 44 which hold the type-carrier between them and carry it with them as soon as the rack is displaced. These arms 44 pass through the front open part of the type-carrier guiding frame so that the height-adjustment of the said frame for the purpose of changing the row of types in use can be effected without hindrance on the part of the arms 44. On the other hand the rack 36 together with the arms 44 can be rocked forwardly in the direction of the arrow 2 (Fig. 7) so as to be withdrawn from the stirrups 39 of the slides 40 so that the type-carrier guiding frame together with the type-carrier can be removed from the pins 17 without difficulty, for example for the exchange of a type, the cleaning of the types or for the examination thereof.

The toothed sector 37 which engages with the rack 36 is mounted upon an upright shaft 45 (Figs. 1, 2, 3 and 13) which carries at its lower part a circular disk 46 with two radial notches 47. By means of these notches the rotation of the shaft 45 to the left or to the right can be effected by forwardly moving the one or the other of two pins 48 respectively on two shafts 49 in order to bring the said pin into the notch opposite to it and effect the rotation of the disk 46. The rotation of the shaft 45 to the left corresponds, through the medium of the toothed sector 37 and the rack 36, to a displacement of the type-carrier to the left and this rotation is effected in a manner hereinafter described by the depression of any one of the left-hand group, while the rotation of the said shaft 45 to the right and the corresponding displacement of the type-carrier is the result of the operation of a key of the right-hand group. As the means employed for this purpose are the same for both groups it will suffice in the following description to describe the means appertaining to the left-hand group only. The shaft 49 in connection with this group is connected by means of a short arm 50 and a link 51 with a lever 53 pivoted at 52 so that it can move in a horizontal plane, the said lever 53 being connected by means of an articulation 54 with a swinging lever 57 carrying the armatures of two electromagnets 55 and 56. One of these electro-magnets, namely that designated 55, serves when energized to swing the shaft 49 outwards by means of the members 53 and 51 in such a manner that its pin 48 is thrown forwards into the corresponding notch 47 of the disk 46 in order to effect by a powerful blow the rotation of the shaft 45 to the left and so to slide the type-carrier also to the left. When the excitation of the electro-magnet 55 is interrupted the other electro-magnet 56 comes into operation and returns the shaft 49 together with the parts in connection therewith into its position of rest in which it is retained by means of a flat spring 58 engaging its under part (Figs. 3 and 9).

The type-carrier and the actuating rack 36 are retained in their initial position or position of rest at the middle of a stroke (Fig. 1) in order that they may be moved to the left or to the right by means of the toothed sector 37 according as to whether a key of the left-hand or of the right-hand group is struck. It will be obvious that this initial position or position of rest of the type-carrier must be exactly determined in order that it shall not, by reason of its momentum, move beyond its middle position to either side, in which event, on the next key being operated, an incorrect type adjustment would result. To this end the shaft 45 carrying the toothed sector 37 is provided at its lower part with a transverse rod 61 (Fig. 13) which is provided on each side of the shaft with a flat spring 62 and co-operates with two vertical spring-operated locking pins 63 in such a manner that in their raised or uppermost position the springs 62 are in contact with the locking pins 63 and so prevent the shaft 45 from turning in either direction. The raising of each of the pins 63 is effected by means of a forked lever 65, loosely mounted upon the pin 64, the said forked lever 65 being provided upon its under-side with an inclined surface 66 (Figs. 2 and 12) and being lifted by a pin 67 projecting laterally from the link 51 and which, when the link is moved backwards to its rearmost position, slides on the said surface 66. This backward movement of the link 51 is effected, as already described, by the electromagnet 56 which, when energized, displaces the armature lever 57 in such a manner that the link 51 is withdrawn into its rearmost extreme position.

The paper carriage controlling mechanism does not possess any essential novel features. The paper carriage 68 (Fig. 1) which is immediately behind ink bands 28 and is subjected in the known manner, to the constant pull of a spring, is intermittently moved by means of the armature 69 of an electromagnet 70 which, when energized, releases a pawl 130

72 from the carriage locking-wheel 73 through the medium of a pawl 71 of the armature (Fig. 2) and of a pin 74 on this latter pawl in order to release the carriage until it 5 is again locked by the pawl tooth 75 and on the interruption of the excitation of the electromagnet 70 to enable the pawl 72 to again drop into the next space of the toothed wheel 73. This mode of controlling the paper carriage 10 is known.

In front of the electromagnet armature 69 there terminates a rod 76 (Figs. 1 and 2) which extends from the key-board and is longitudinally movable and subject to the action 15 of a spring. This rod 76 can be pushed backwards through the medium of a special key 77 in order to mechanically displace the armature 69 and to enable the paper carriage to be controlled as desired without the employment 20 of the electric current.

The paper upon which the characters are to be impressed runs in the known manner between controllable rollers and, in the construction described, permits the writing to 25 be immediately visible.

The electric contact devices form one of the essential features of the invention. As in the case of the other mechanisms I will here only describe the mechanism in connection 30 with the left-hand group of keys.

In the first place mention must be made of a main contact 80 arranged upon, and insulated from, the machine frame and the movable contact member of which is in the form 35 of a rotatable cam 81 (Fig. 12) and is connected by means of the arm 82 and the link 83 with an arm 84 (Figs. 12 and 13) which is mounted upon, and insulated from, the corresponding shaft 49 so that when the latter 40 is rotated by the operation of a key the current which was cut off is allowed to enter the machine.

In the second place there is provided a contact wheel 85 pivotally mounted at the point 45 86 and having three contact arms 87, 88 and 89 (Fig. 11), the said wheel being adapted to be turned by means of an arm 91 which engages with a fork 90 of the wheel and is mounted upon the corresponding rocking 50 shaft 5 actuated by the key-levers. If, therefore, this rocking shaft be turned by the depression of a key, the contact wheel 85 is simultaneously turned. The three contact arms of the latter coöperate frictionally with 55 three corresponding contact springs 92, 93 and 94 and control thereby the current supply for the type-carrier driving electromagnet 55, the paper carriage controlling electromagnet 70 and the type-carrier return 60 electromagnet 56 as will be more particularly referred to in the description of the operation of the machine. The contact wheel 85 and the three contact springs 92, 93 and 94 are carried by a common support 95 65 which is mounted upon, and insulated from,

the machine frame. The arm 91 is secured upon the rocking shaft 5 by means of an insulating bush (Fig. 13) so that this part also is insulated from the machine frame. Of the contact springs 92, 93 and 94, the spring 93 70 is subjected to the action of an insulated finger 96 on the shaft 49 (Fig. 13) in such a manner that at the initial position or position of rest of the parts it is pressed backwardly by this finger and so held removed from the 75 corresponding arm 88 of the contact wheel 85; this position is shown in Fig. 13. The return of the contact wheel 85 after its rotation is effected by the action of a spring 97 (Fig. 13) which engages the arm 91 with the 80 interposition of an insulator.

To describe the operation of the machine reference is made to the diagram (Fig. 14) in connection with which it is to be distinctly understood that for the purpose of clearness 85 several parts are not shown, while other parts are assumed to be differently constructed from the parts shown in the machine illustrated in Figs. 1 to 13. For similar parts, however, the same numerals of reference are employed. It is again only the left-hand side of the machine which is taken into consideration.

Normally the contact arm 87 of the contact wheel 85 rests upon the contact spring 92, the main contact 80 being however broken. No current therefore flows to the machine. The type-carrier is secured in its initial or middle position by the locking pins 63 which are raised and lie in front of the 100 transverse bar 61 of the shaft 45 which actuates the type-carrier. If now any one of the key-levers 1 of the left-hand group be depressed the following operations take place. Firstly, the rocking shaft 5 turns in the direction of the arrow *x* (Fig. 9) and by means of a finger 98 mounted upon it and of a bell crank lever 99 which engages a short arm 100 on the shaft 49, the said shaft 49 is turned in the direction of the arrow *v* (Figs. 2, 9, 12, 13 and 14), whereby the main contact 80 (Fig. 14) is closed by the contact cam 81 and current is switched on. The contact wheel 85 is then, through the medium of the arm 91 of the rocking shaft 5, rotated in the direction 105 of the arrow *s* (Figs. 13 and 14) in order to effect the following contact makings and breakings. Finally through the medium of the bell-crank lever 7 connected to the actuated key-lever the corresponding type-carrier 110 locking pin 9 is pushed backwards. The described rotation of the shaft 49 results in further movements. The lever 53 is through the medium of the link 51 (Figs. 3 and 13) so turned that the armature lever 57 which 115 normally lies against the electro-magnet 56 (position I of Fig. 14) is moved somewhat towards the electromagnet 55 (position II of Fig. 14). Then, by the displacement of the link 51, its pin 67 will slide from the cam 120

125

surface 66 of the forked lever 65 (Fig. 2) in order to permit of the downward movement of the left-hand locking pin 63 and so releasing the type-carrier drive for displacing the said carrier to the left. Finally the rotation of the shaft 49 withdraws the finger 96 from the contact spring 93 so that the latter can assume its position of contact (in Fig. 14 this finger is merely shown in connection with the contact wheel 85). The rotation of the contact wheel 85 in the direction of the arrow *s* makes contact between the arm 89 and the spring 94, while the contacts on the arms 87 and 88 (for the latter arm notwithstanding the release of the spring 93 from the finger 96) are broken. The result is that a current flows from the positive pole through the wire 101, over the closed contact 80 through the connection 102, the contact 89, 94, electro-magnet 55 and through the wire 103 back to the negative pole in connection with the machine frame so that the electro-magnet 55 is now energized in order to powerfully pull the armature lever 57 (position III shown in Fig. 14) and, through the medium of the link 51 and while still retaining the closed contact at 80, to turn the shaft 49 in the direction above referred to to such an extent that its bent pin 48 snaps into the corresponding notch 47 of the disk 46 and through the medium of the shaft 45 and the toothed gear 36, 37, displaces the type-carrier 13 to the left. The latter is then retained or stopped by the projected stopping pin 9 in such a position that the type corresponding to the key struck comes to lie with its rod 25 exactly in front of the head of the type striking hammer 31, while simultaneously, through the pin 9 connected to the positive pole of the source 40 of current by means of the insulated rails 11, contact is made with the contact spring 43 of the left-hand slide 40 of the type-carrier (Fig. 8), whereby a circuit is closed by a wire 104, the type actuating electromagnet 32, the rails 11, the pin 9, and the type-carrier 13 back to the negative pole connected to the machine frame so that the electromagnet 32 is energized and the hammer 31 impelled against the rod 25 of the type set up in order 45 to obtain an impression. If now the key-lever which has been operated is released, the contact wheel 85 is turned back by means of the spring 97 (Fig. 13). The contact 89, 94 is then broken so that the electromagnet 55 is cut out of the circuit. The contacts 87, 92 and 88, 93 are then closed by the contact wheel. The closure of the first contact 87, 92 effects the switching in of the electromagnet 56 in order to attract the armature lever 57. While the latter moves from the position III into the position II (Fig. 14), the shaft 49 is turned back by the link 51 in such manner that the type-carrier is through the medium of the pin 48, the disk 46, the shaft 45 and the toothed gear 37, 36 returned

to its initial position. The contact 80 still however remains closed. Simultaneously, the contact 88, 93 by means of the spring 93 being in its contact position closes the circuit 101, 80, 102 over the paper carriage operating electro-magnet 70, and wire 105, in order to set in the controlling of the paper carriage by the attraction of the armature 69 and by the succeeding breaking of the corresponding circuit to permit this to be carried out.

The continued movement of the armature lever 57 under the action of the electromagnet 56 brings it finally from the position II into the initial position I and during this portion of the movement the complete return to the initial position of the parts of the machine takes place. The link 51 is then withdrawn into its rearmost position and the shaft 49 completely returned so that the pin 48 completely leaves the notch 47 in the disk 46 and the spring 93 by means of the finger 96 is forced out of its contact position and finally the main contact 80 is broken and current is cut off (Fig. 13). Furthermore, on the complete withdrawal of the link 51, the pin 67 thereof slides on the cam surface 66 of the forked lever 65 (Fig. 2), in order to raise the latter and with it the locking pin 63 and thereby, by means of the transverse rod 61, lock the shaft 45 and the type-carrier driving gear until the next key is struck. In this manner all the parts have re-assumed the initial position shown in full lines in the drawing. When another key is struck the above described operations are repeated, that is to say, shortly described, the closure of the main contact 80, the excitation of the electromagnet 55, the displacement of the type-carrier, the excitation of the type-impressing electromagnet 32, the interruption of the excitation of the electromagnet 55, the return of the type-carrier by means of the electromagnet 56 and the interruption of the excitation of the type impressing electromagnet 32, the putting in circuit of the paper carriage operating electromagnet 70, the locking of the type-carrier in its initial position by means of the locking pins 63 and finally the breaking of the main contact 80.

It will be obvious that some of these operations take place simultaneously and that some follow one another quickly so that the characters can be formed with great speed. Moreover, for exciting the various electromagnets only a weak source of current (for example of 6 volts) is required as all the electromagnets are separately and directly connected to the source of current. The contacts are all frictional spring contacts so that they automatically remain clean and also provide an intimate contact. The arrangement of the contacts controlling the electromagnets 55, 70 and 56 upon one and

the same support makes it more easy and convenient to repair and exchange individual contact parts.

What I claim is:

- 5 1. In an electric typewriting machine, the combination with a group of key-levers, a common rocking shaft arranged to be operated by the key-levers, a movable type-carrier, an electromagnetic adjusting device 10 for this latter, an electromagnetic paper-carriage controlling device and an electromagnetic device for the return of the type-carrier into its initial position, of one and the same movable contact wheel connected to 15 the said rocking shaft and adapted to control three contacts in such a manner that on striking and releasing one or the other of the key-levers the said contact wheel is displaced so as to directly control a first contact for 20 the said type-carrier adjusting device; a second contact for the said paper-carriage controlling device and a third contact for the type-carrier return device, substantially as described.
- 25 2. In an electric typewriting machine, the combination with a group of key-levers, a common rocking shaft arranged to be operated by the key-levers, a movable type-carrier, an electromagnetic adjusting device 30 for this latter, an electromagnetic paper-carriage controlling device, an electromagnetic device for the return of the type-carrier into its initial position and a locking device for the type-carrier in the said position, of one 35 and the same movable contact wheel connected to the said rocking shaft and adapted to control three contacts in such a manner that on striking and releasing one or other of the key-levers the said contact wheel is displaced so as to directly control a first contact for 40 the said type-carrier adjusting device, a second contact for the said paper carriage controlling device and a third contact for the type-carrier return and locking devices, substantially as described.
- 45 3. In an electric typewriting machine, the combination with a group of key-levers, a common rocking shaft arranged to be operated by the key-levers, a movable type-carrier, an electromagnetic adjusting device 50 for this latter, an electromagnetic paper-carriage controlling device, an electromagnetic device for the return of the type-carrier into its initial position, a locking device for the 55 type-carrier in said position and a current cut off device, of one and the same movable contact wheel connected to the said rocking shaft and adapted to control three contacts in such a manner that on striking and releasing one or other of the key levers the said contact wheel is displaced so as to directly control a first contact for the said type-carrier adjusting device, a second contact for the 60 said paper carriage controlling device and a third contact for the type-carrier return and

locking devices, and also for the current cut off device, substantially as described.

4. In an electric typewriting machine, the combination with a group of key-levers, a common rocking shaft arranged to be operated by the key-levers, a movable type-carrier, an electromagnetic adjusting device for this latter, an electromagnetic paper carriage controlling device, an electromagnetic device for the return of the type-carrier into its initial position and a current make and break main contact device, of one and the same movable contact wheel connected to the said rocking shaft and having three arms adapted to frictionally coöperate with three contact springs connected in electric circuit with the said electromagnetic devices, and a secondary shaft arranged dependently upon the said rocking shaft and adapted to control the said main contact device in such a manner that when a key-lever is struck, the said secondary shaft is turned somewhat so as to effect the closure of the main contact device and the complete closing of the circuit through the said electromagnetic devices, substantially as described.

5. In an electric typewriting machine, the combination with a group of key-levers, a common rocking shaft arranged to be operated by the key-levers, a movable type-carrier, an adjusting electromagnet for this latter, a paper carriage controlling electromagnet, a type-carrier return electromagnet and a locking device for the type-carrier in its initial position, of one and the same movable contact wheel connected to the said rocking shaft and adapted to control three contacts for the circuits of the said electromagnets, an armature lever common to the said type-carrier adjusting and return electromagnets, and a shifting member connected to the said armature lever and adapted to control the aforesaid locking device in such a manner that on the attraction of the said armature lever by the action of the type-carrier return electromagnet in circuit, the locking device, is caused to lock the type-carrier in its initial position, after the return of such carrier, substantially as described.

6. In an electric typewriting machine, the combination with a group of key-levers, a common rocking shaft arranged to be operated by the key levers, a movable type-carrier, an adjusting electromagnet for this latter, a paper carriage controlling electromagnet and a type-carrier return electromagnet, of one and the same movable contact wheel connected to the said rocking shaft and adapted to control three contacts for circuiting the said electromagnets, a type-carrier driving shaft arranged so as to be actuated from the said type-carrier adjusting and return electromagnets, a transverse rod carried by the said shaft, a locking pin to coöperate with the said rod and means depending upon

- the said type-carrier return electromagnet for shifting the said locking pin in such a manner that when the type-carrier is returned into its initial position the said means are actuated to engage the pin with the said shaft crossing rod so as to prevent the shaft from being turned out of its initial position, substantially as described.
7. In an electric typewriting machine, the combination with a group of key-levers, a common rocking shaft arranged to be operated by the key-levers, a movable type-carrier, an adjusting electromagnet for this latter, a paper carriage controlling electromagnet and a type-carrier return electromagnet of one and the same movable contact wheel connected to the said rocking shaft and adapted to control three contacts for circuiting the said electromagnets, a type-carrier driving shaft carrying a cam with an open notch, and a secondary shaft provided with a striking pin opposite to the said cam, normally disengaged therefrom and arranged so as to be actuated from the type-carrier adjusting and return electromagnets in such a manner that by the action of these electromagnets the said striking pin may be quickly struck into and withdrawn from the notch of the said cam with the object of turning the said type-carrier driving shaft forwards and backwards, substantially as described.
8. In an electric typewriting machine, the combination with a group of key-levers, a common device for controlling circuit connections under the action of the said key-levers, and a slidable type-carrier, an adjusting gear for this latter, having a movable rack, a guide for this rack, coupling arms on the latter engaged with the type-carrier and means allowing the disengagement of the said arms from the type-carrier so as to free the latter, substantially as described.
9. In an electric typewriting machine, the combination with a group of key-levers, a common device for controlling circuit connections under the action of the said key-levers, a slidable type-carrier, a group of type-carrier stopping pins arranged to be operated by the key-levers, an electromagnetic type impressing device and a type-carrier driving gear, of a contact spring device in connection with the type-carrier adapted to frictionally engage with that of the said stopping pins which has been operated, in order to make an intimate electric circuiting contact over the said electromagnetic type impressing device, substantially as described.
10. In an electric typewriting machine, the combination of a group of key-levers, a common device for controlling circuit connections under the action of the said key-levers, a slidable type-carrier, a driving gear for the said type-carrier and a striking hammer to effect the type impressions, the said type-carrier having spring actuated types provided with a supporting rod to be struck by the said hammer and with a guiding pin to prevent them from rocking, substantially as described.
- In witness whereof I have hereunto signed my name in the presence of two subscribing witnesses.

JOSEPH LEMBLÉ.
